UNITED STATES PATENT OFFICE.

HENRY PRICE BALL, OF NEW YORK, N. Y., ASSIGNOR TO GENERAL ELECTRIC COMPANY, A CORPORATION OF NEW YORK..

RHEOSTAT.

No. 873,006.

Specification of Letters Patent.

Patented Dec. 10, 1907.

Application filed December 21, 1905. Serial No. 292,720.

To all whom it may concern:

Be it known that I, HENRY PRICE BALL, a citizen of the United States, residing at New York, county of New York, State of New York, have invented certain new and useful Improvements in Rheostats, of which the following is a specification.

This invention relates to devices for controlling electric motor circuits and has for its object the provision of a device of this character which will be protected against injury due either to abnormal load conditions or careless handling and which will be simple of construction and operation and at the same time thoroughly reliable, safe and durable.

My invention relates more specifically to controlling devices of the type known as starting rheostats in which a sufficient resistance is included in series with the motor at starting to prevent a dangerous rush of current, resistance being gradually cut out as the motor speeds up until it is finally short-circuited. In devices of this character it is essential that provision be made whereby the circuit cannot be closed except through the protecting resistance. It is also desirable that means be provided whereby if the resistance is cut out too rapidly so as to endanger the motor and the starting resistance, the circuit will be opened and it will be necessary to return the controlling arm to starting position before it can be again closed.

In carrying out my invention I provide a controlling arm adapted for sliding engagement with a series of contact studs, said controlling arm being pivoted so as to move in a plane at right angles to the plane of the contacts so that the circuit may be broken at any contact without passing over the other contacts. This controlling arm I connect with a controlling handle by means of a toggle, and an overload magnet is provided to knock out the toggle and allow the controlling arm, which is biased to open position, to break the circuit. A no-voltage magnet is also provided and is so arranged as to act upon a projection of the operating handle to hold the arm in operating position. Upon failure of voltage the handle is released and the circuit broken. I also provide means whereby the circuit when once it is opened cannot be closed without moving the controlling arm to the starting position but which permits the opening of the circuit in any position.

My invention further consists in the features of construction and the arrangement and combination of elements hereinafter set forth and particularly pointed out in the claims annexed to and forming a part of this application.

In the drawings illustrating one embodiment of my invention, Figure 1 is a plan view of the device; Fig. 2 is a side elevation of the same, part of the base being broken away; Fig. 3 is a similar view showing the position of the parts when the circuit is broken; and Fig. 4 is a diagram of circuits.

Referring to the drawing, 10 is an insulating base of slate or soapstone provided with a series of contact plates or studs 11 arranged in the arc of a circle and forming terminals of a starting resistance 12. Mounted within the base and concentric with the studs 11 is a circular metallic casing 13 having a supporting flange 14 which rests upon the base. A collar 15 is secured to the flange 14 and base 10 by means of bolts 16, the contacting faces of the parts 14 and 15 being cut away so as to afford a bearing for flange 17 of sleeve 18. The controlling arm 19 is pivoted at 20 in brackets 21 of sleeve 18 and is spring-pressed in the position shown in Fig. 3 and in dotted lines in Fig. 2 by means of the spring 22. The arm 19 is preferably in the form of a bell crank lever, one end of which is provided with an engaging surface or brush 23 for engaging the contact studs, the other end being connected with an extension 24 of the operating handle 25 by means of the links 26 and 27, forming a toggle. The handle 25 is pivoted in a bracket 28 of the sleeve 18 arranged diametrically opposite to the brackets 21. The handle 25 is also provided with a circular extension 29 extending in proximity to the sleeve 18 so as to be under the control of the magnet 30 within the sleeve and concentric therewith. Directly under this magnet is a second magnet 31 within the casing 13. These magnets are concentrically arranged and a single core 32 having an enlarged head 33 on the underside is adapted to reciprocate therein, a spring 34 normally forcing the head away from the casing as shown in Fig. 3. The upper end of the core passes through the extension 29 which is cut away to receive it and comes opposite to the toggle joint when the controlling arm is down in engagement with the

contact studs 11, as shown in full lines in Fig. 2. A latch 35 pivoted to the operating handle is spring-pressed toward the collar 15 by means of a spring 36 so as to engage a flange 37 thereon. This flange extends only a portion of the distance around the collar, as shown in Fig. 1 and is slotted at 38 so as admit the latch 35.

The operation of my device will be clearly understood from the foregoing description from which it will be seen that the controlling arm 19 is normally biased away from the contact studs and is forced into contact therewith by means of the handle 25. With the parts in the position shown in Fig. 3, the circuit is broken and the latch 35 is in engagement with the flange 37 so as to hold the operating handle and hence the controlling arm in the position shown. The controlling arm cannot, therefore, be forced into engagement with the studs until it is turned to the left from the position shown in Fig. 1, sufficiently to allow the latch 35 to pass through the slot 38. This will be the starting position of the rheostat. When this point is reached the handle may be drawn up and the toggle being straight, the operating arm will be moved against the tension of the spring 22. As soon as contact is made between the arm and the studs the magnet 30 is energized and its core 30' attracts the extension 29 of the operating handle, as shown in Fig. 2. The controlling arm may now be moved along to the right by means of the handle to cut out resistance. At any position of the controlling arm, should the load become excessive, due to too rapid movement of the arm or to other causes or when the arm has reached the short-circuited position on the last stud, the overload magnet 31 will attract the head 33 against the tension of the spring 34 and the projecting end 32 will strike the toggle joint and break the same allowing the controlling arm to take the position shown in dotted lines in Fig. 2. Likewise upon failure of voltage from any cause or with the arm in any position, the no-voltage magnet 30 will release the extension 29 of the operating handle and allow the parts to assume the position shown in Fig. 3. In either case, after the circuit has been broken, it will be impossible, as before stated, to again close the circuit until the arm has been moved to starting position with the operating handle opposite the slot 38.

The arrangement of the circuits is shown in Fig. 4 and is extremely simple. In the arrangement shown the magnet 31 is arranged in series with the starting resistance 60 and the armature so that when the starting arm is moved on to the first stud, current passes from a line at L through the magnet coil 31, controlling arm 19, resistance 12, conductor 39 to armature A and back to line 65 at L', the current to the shunt field passing

from the pivotal point of the controlling arm at 41 through the magnet 30 and field F back to line.

It will thus be seen that I have provided a rheostat which it is impossible to destroy either by improper handling or from overloads due to other causes. The opening of the circuit through the controlling arm is independent of the operating handle so that should the operator attempt to hold the arm on any stud for too long a time, the circuit will be broken without movement of the handle. It will then be necessary that the arm be again moved to starting position before the circuit can be closed.

While I have described a specific construction and arrangement of parts, it should be understood that I do not limit my invention thereto, since various modifications may be made therein without departing from the spirit of my invention, the scope of which is set forth in the claims hereto annexed.

What I claim as new and desire to secure by Letters Patent of the United States, is,—

1. A rheostat comprising a series of contacts, a controlling arm mounted for sliding engagement therewith to vary the resistance, and means for breaking the circuit at any of said contacts by disengaging said arm therefrom upon the occurrence of underload or overload conditions.

2. A starting rheostat comprising a series of contacts, a controlling arm mounted to successively engage the same to vary the resistance, means for disengaging said arm from any of said contacts to break the circuit upon the occurrence of underload or overload conditions, and means for preventing a reengagement until the arm is brought to starting position.

3. A starting rheostat comprising a series of contacts, a controlling arm adapted for sliding engagement with said contacts but biased therefrom and pivoted for movement in a plane at an angle to the plane of said contacts, and means for preventing engagement between said arm and said contacts until the former is moved to the starting position.

4. A rheostat comprising a series of contacts, a controlling arm adapted for sliding engagement with said contacts but biased therefrom and pivoted for movement in a plane at an angle to the plane of said contacts, means for holding said arm in engagement with said contacts during normal operation, and means for releasing the same in any position upon the occurrence of underload or overload conditions.

5. A starting rheostat comprising a series of contacts, a controlling arm adapted for sliding engagement with said contacts but biased therefrom and pivoted for movement in a plane at an angle to the plane of said contacts, means for preventing engagement

between said arm and said contacts until the former is moved to the starting position, and means for releasing the same in any position upon the occurrence of underload or 5 overload conditions.

6. A starting rheostat comprising a series of contacts, a controlling arm adapted for sliding engagement with said contacts but biased therefrom and pivoted for movement 10 in a plane at an angle to the plane of said contacts, means for holding said arm in engagement with said contacts during normal operation, means for releasing the same in any position upon the occurrence of under- 15 load or overload conditions, and means for preventing engagement between said arm and said contacts until the former is moved to the starting position.

7. A rheostat comprising a series of contacts, a controlling arm pivoted for movement in a plane at an angle to the plane of said contacts and adapted to successively engage the same but biased from the contacts, means for holding said arm in engagement with said contacts during normal operation, an operating handle, and means for releasing said arm independently of said handle.

8. A rheostat comprising a series of contacts, a controlling arm adapted for sliding engagement with said contacts but biased therefrom, means for holding said arm in engagement with said contacts during normal operation, an operating handle, and an electromagnetic device for releasing said arm independently of said handle.

9. A rheostat comprising a series of contacts, a controlling arm therefor, an operating handle, toggle connections between said 10 arm and said handle and means for opening the circuit upon the occurrence of abnormal conditions therein.

10. A rheostat comprising a series of contacts, a controlling arm therefor biased to 15 open circuit position, an operating handle, toggle connections between said arm and said handle, and a no-voltage magnet acting upon said handle to hold said arm in operative position.

11. A rheostat comprising a series of contacts, a controlling arm adapted for sliding engagement with said contacts but biased therefrom, an operating handle, toggle con-

nnections between said arm and said handle for holding the former in engagement with 55 said contacts during normal operation, and an overload device acting upon said toggle to release said arm.

12. A rheostat comprising a series of contacts, a controlling arm therefor biased to 60 open circuit position, an operating handle, toggle connections between said arm and said handle, a no-voltage magnet acting upon said handle to hold said arm in operative position, and an overload device acting upon 65 said toggle to release said arm.

13. A starting rheostat comprising a series of contacts, a controlling arm therefor biased to open circuit position, an operating handle, 70 toggle connections between said arm and said handle, a no-voltage magnet acting upon said handle to hold said arm in closed circuit position, and means for preventing movement of the arm to the closed circuit position until it has been moved to the starting position. 75

14. A rheostat comprising a series of contacts, a movable member mounted to rotate in a plane parallel to the plane of the contacts, a controlling element pivoted thereto 80 for movement in a plane at an angle to the plane of the contacts, a similarly pivoted operating handle, link connections between said handle and said arm, and an electromagnetic device for holding said arm in operative 85 position and for releasing the same upon the occurrence of underload conditions.

15. A rheostat comprising a series of contacts, a movable member mounted to rotate in a plane parallel to the plane of the contacts, a controlling element pivoted thereto 90 for movement in a plane at an angle to the plane of the contacts, a similarly pivoted operating handle, toggle connections between said handle and said arm, and electromagnetic 95 devices for holding said arm in operative position and for releasing the same upon the occurrence of underload or overload conditions.

In witness whereof, I have hereunto set my hand this 18th day of December, 1905.

HENRY PRICE BALL.
